(57) **CLAIM**

The ornamental design of a laser alignment tool, as shown and described.

DESCRIPTION

FIG. 1 is an isometric view of a laser alignment tool in accordance with my new design, in which the portions in phantom form no part of the claimed design;

FIG. 2 is a front end elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.
